UNITED STATES PATENT OFFICE.

ROBERT S. KENT, OF BROOKLYN, NEW YORK.

KILN FOR REVIVIFYING CHAR.

1,004,176.

Specification of Letters Patent. Patented Sept. 26, 1911.

Application filed June 3, 1911. Serial No. 631,098.

To all whom it may concern:

Be it known that I, ROBERT S. KENT, a citizen of the United States, and a resident of Brooklyn, in the county of Kings and 5 State of New York, have invented certain new and useful Improvements in Kilns for Revivifying Char, of which the following is a specification.

My present invention is principally in the 10 nature of an improvement upon that disclosed in Patent No. 972002, granted to me October 4, 1910, for improving the construction of kilns used in sugar refineries for the 15 purpose of fully drying, and burning out organic waste material from, the animal charcoal or bone-black known as "char" generally used in sugar refining for removing coloring matter etc. from the sugar liquors.

20 My present improvements are directed particularly to increasing the efficiency of a kiln of the general type disclosed in my aforesaid patent and protection given to the upper portions of the retorts or pipes containing the drying char in a kiln of this type.

In my aforesaid patent I have disclosed as the principal feature of the invention a wall or walls of sufficient height to change the 20 course of the hot products of combustion, etc., rising from the fire-box, and deliver them at such a point in the kiln that they will come in contact with the upper parts of the retort pipes before they come in contact 25 with the lower portions of these pipes, while at the same time increasing the draft in the kiln and producing more perfect combustion as a result of bringing the incompletely 30 burned gases, etc., rising from the fire-box, into contact with a highly heated wall or 35 walls of great area. In the present improved construction all of these advantages are retained and the additional advantages 40 before specified secured. The baffle-walls of 45 the kiln shown in my aforesaid patent were somewhat higher than those now used, and the two walls of each of those kilns were spaced at substantially the same distance 50 apart from the top to the bottom of the walls, and the space between the walls was so great that the hot gases came in contact 55 with the upper parts of the retorts almost immediately. In the later kilns, somewhat lower walls have been used than those employed in the first kilns embodying the invention, and instead of building up the two 60 baffle-walls in such a manner as to maintain a uniform distance between them from the bottom to the top of the walls, these walls have been so formed as to provide near the 65 top thereof a reduced outlet into the upper part of the kiln for the products of combustion from the furnace, which reduced outlet, whether formed by one opening or by a plurality of openings, is preferably so located 70 that the gases, etc., will be delivered into the upper part of the kiln at a point substantially central of the kiln, crosswise thereof, that is to say, at a point substantially equidistant from the two sets of banks of 75 retorts. The reason for this is that in the use of the earlier kilns it was found that while the lower ends of the retorts were thoroughly protected their upper ends were not 80 always as well protected as they should be 85 from the hottest heat of the rising gases. Because of this it was found desirable to modify the original construction in such a manner as to reduce still further the temperature of these gases at the points where 90 they came in contact with the upper ends of the retorts. It was found that a sufficient reduction of the temperature of these gases could be effected, without loss of any of the 95 advantages of the earlier and higher straight walls substantially equidistant from each other at all points, by bringing such walls nearer together at their upper ends and providing a reduced outlet at such point substantially centrally of the two banks of 100 retorts, measured crosswise of the kiln. At 105 the same time the height of these walls was made somewhat less than in the earlier kilns with a consequent saving in material, and with equally and indeed more perfect 110 combustion of the rising gases, etc., due in part to the more thorough mixing or commingling of the various products of combustion and other elements of these gases, etc. This 115 discharge of said hot products from such a centrally located outlet at the top of the baffle-walls involved an increase in the distance which said gases were compelled to travel before they came in contact with the upper parts of the retorts, and it was found 120 that with the baffle-walls so modified and the gases discharged from the central outlet in the manner described, said gases when they 125 came in contact with the upper parts of the retorts were at a considerably lower temperature than in the kilns at first constructed to embody the invention, and that there 130

was no longer any danger of burning the walls of the retorts at the upper ends thereof.

The feature of delivering the products of combustion into the upper portion of the kiln nearer the central, longitudinal zone thereof than in my first kilns, and from that zone delivering them into the zone of the retort pipes at a lower temperature than the hot products of combustion delivered into the corresponding zone in my first kilns, may be embodied in various specific types of kilns, several of which will be hereinafter described and claimed and are illustrated in the accompanying drawings, in which—

15 Figure 1 is a substantially central, vertical, longitudinal section of a kiln embodying this invention and capable of producing the results just described; Fig. 2 is a substantially central, cross-section of the same, partly in front elevation; Fig. 3 is a substantially central, cross-section similar to Fig. 2, of a portion of a kiln illustrating one modification of the construction shown in Figs. 1 and 2; Fig. 4 is a plan of the 20 main portion of the same; Fig. 5 is a view similar to Fig. 3 of another modification of the construction shown in Figs. 1 and 2, and Fig. 6 is a sectional underside view of a portion of the same.

30 Most of the parts constituting the kiln are or may be of any well-known or suitable construction. In these kilns all of the walls are usually of brick, and this is the construction shown herein, the kiln being designated generally by K, the front and rear walls by 35 2 and 3, and the side walls by 4 and 5. The kiln is also illustrated here as having an arched roof 6, of a type well understood in the art. Beneath the center of the kiln 40 proper is a fire-box 7 having a grate 8, this fire-box extending in the present case about two-thirds of the way back from the front of the kiln and being fired only from the front, although the fire-box might extend all the way through and be fired from both ends, as in another type of kiln in general use. Kilns of this type contain a large 45 number of retorts in the form of pipes extending from the top to the bottom of the kiln, these pipes receiving their supplies ordinarily from a superimposed char-drier (not shown), and delivering the purified charcoal from their lower ends into cooler-tubes (not shown) located below the floor of 50 the kiln. These retort pipes are ordinarily arranged in two sets at opposite sides of the fire-box and are shown herein. The retorts of the different sets are designated respectively by 9 and 10. The walls of the retorts 55 are generally of three different thicknesses, being thickest at the upper ends and thinnest at the lower ends, as illustrated in Fig. 2, while the intermediate portion is of an intermediate thickness. Prior to the use of 60 the kilns disclosed in my aforesaid patent

retorts of this construction burned out quickly at their lower ends, because the most highly heated products of combustion were delivered in such prior kilns directly in contact with the lower ends of the retorts where the retorts were less able to resist the high temperature. This was avoided in the kiln of my aforesaid patent and a more perfect drying of the descending char in the retorts effected than when the gases and other products of combustion from the fire-box were circulated upward and came in contact first with the lower ends and afterward with the upper ends of the retorts, as in kilns used prior to the invention of my aforesaid patent. In my improved kiln shown herein, the same great advantages are obtained by reversing the direction of flow of the products of combustion—that is to say, by causing such gases, etc., to flow downward from the tops to the bottoms of the retorts—that were obtained in the kilns constructed as specifically shown and described in my said patent. Here, as there, I make use of one or more baffle-walls of relatively great height, 80 coöperative with the fire-box and one or both sets of retorts for the purpose of directing the products of combustion in the first instance up to the upper portions of the retorts, after which they pass down to 85 the lower ends of said retorts.

As before stated, my present improvements may be embodied in various constructions all embracing the same general features common to my improved kiln, as distinguished from the kiln of my aforesaid patent, but all differing specifically from one another. In each case two baffle-walls, such as 11, are preferably employed and are built of brick-work to form between them a 100 draft passage for the upward flow of the products from the fire-box, and downward passages outside such baffle-walls and between them and the respective set of retorts to suitable outlets preferably placed at or 105 near the bottom of the kiln and at opposite ends and sides thereof, that is at the four corners of the kiln, as indicated at 12. The preferred construction is illustrated in Figs. 1 and 2 in which these walls of brick-work 115 are built up substantially as illustrated with their outer sides substantially vertical and their inner surfaces gradually approaching each other as by stepping up the bricks in the manner indicated. In these views, by the gradual reduction of the distance between the walls, a reduced or contracted outlet is formed at 14, which is located at the center of the kiln crosswise thereof, and also at the central point between the banks 120 of retorts, and extends from end to end of the kiln. Such a construction as this directs all of the rising gases, etc., into the central portion of the space under the arch of the kiln in such a manner that they come in con- 130

tact with the upper parts of the retort-pipes first, and afterward come in contact with the lower ends of these pipes, while at the same time all of the other advantages result which have hereinbefore been mentioned. 5 An important feature of this variety of the improved or modified type of kiln is that repairs can be made readily to the walls 11.

In Figs. 3 and 4 there is illustrated a 10 different variety of the improved or modified type of kiln in which the baffle-walls 11 are of substantially the same height as in Fig. 2 and are in many respects quite similar in construction, the main differences 15 being that the bricks are stepped-up both at the inner and outer faces of the two walls, but are not brought so close together as in the brick-work shown in Fig. 2 and that the reduced outlet for the gases, etc., is formed 20 by tiles, such as 15, having suitable openings at their edges. These tiles may be of any suitable size and shape. Both round and rectangular openings or outlets are illustrated in Fig. 4 at 16 and 17. These 25 walls also can be readily repaired.

Figs. 5 and 6 illustrate another variety of the modified or improved type of kiln in which the baffle-walls 11 instead of being carried straight up, and then stepped 30 to bring them closer together to form a reduced outlet, are built up and connected at their upper ends by forming an arch of brick-work having suitable openings, such as 18, extending through it. These openings 35 may be of any suitable size and shape and located in any desired positions, provided the gases are permitted to escape through them substantially centrally of the kiln measured crosswise thereof. As here 40 shown, there are three rows of these openings, the openings of alternate rows being staggered relatively to each other.

All of the different forms of kiln illustrated embody the same general principle 45 of operation, differing from one another in the specific details of their construction and as to the ease with which repairs can be made.

What I claim is:

1. In a kiln for revivifying char, the combination with a fire-box, of a set of retort pipes at one side of said fire-box, and means for delivering the major portion of the products of combustion from said 50 fire-box into the upper portion of the kiln at a point distant from said retort pipes and circulating such products in contact with first the upper and then the lower portions of said pipes.
2. In a kiln for revivifying char, the combination with a fire-box, of a plurality of retort pipes arranged in sets at opposite sides of the fire-box, and means for circulating the major portion of the products of combustion from said fire-box in contact 55 with first the upper and then the lower portions of said retort pipes, said means including a pair of baffle-walls disposed lengthwise of the kiln between the fire-box and the respective sets of retort pipes and

with first the upper and then the lower portions of said retort pipes, said means including a pair of baffle-walls disposed lengthwise of the kiln between the fire-box and the respective sets of retort pipes and having means for forming between them at their upper ends a reduced outlet for said products of combustion. 70

3. In a kiln for revivifying char, the combination with a fire-box of a plurality of retort pipes arranged in sets at opposite sides of the fire-box, and means for circulating the major portion of the products of combustion from said fire-box in contact with first the upper and then the lower portions of said retort pipes, said means including a pair of baffle-walls disposed lengthwise of the kiln between the fire-box and the respective sets of retort pipes and having means for forming between them 80 at their upper ends an outlet reduced transversely of the kiln. 85

4. In a kiln for revivifying char, the combination with a fire-box, of a plurality of retort pipes arranged in sets at opposite 90 sides of the fire-box, and means for circulating the major portion of the products of combustion from said fire-box in contact with first the upper and then the lower portions of said retort pipes, said means including a pair of baffle-walls disposed lengthwise of the kiln between the fire-box and the respective sets of retort pipes and having means for forming between them at their upper ends an outlet reduced transversely of the kiln and disposed substantially midway between the two sets of pipes. 95

5. In a kiln for revivifying char, the combination with a fire-box, of a plurality 105 of retort pipes arranged in sets at opposite sides of the fire-box, and means for circulating the major portion of the products of combustion from said fire-box in contact with first the upper and then the lower 110 portions of said retort pipes, said means including a pair of baffle-walls disposed lengthwise of the kiln between the fire-box and the respective sets of retort pipes and having at their upper ends means for delivering said products of combustion into the upper portion of the kiln in the central crosswise zone thereof at a point distant from the retort pipes. 115

6. In a kiln for revivifying char, the 120 combination with a fire-box, of a plurality of retort pipes arranged in sets at opposite side of the fire-box, and means for circulating the major portion of the products of combustion from said fire-box in contact 125 with first the upper and then the lower portions of said retort pipes, said means including a pair of baffle-walls disposed lengthwise of the kiln between the fire-box and the respective sets of retort pipes and 130

having inner walls one of which at its upper end approaches the other and forms with it at the upper ends of the walls a reduced outlet for said products of combustion.

7. In a kiln for revivifying char, the combination with a fire-box, of a plurality of retort pipes arranged in sets at opposite sides of the fire-box, and means for circulating the major portion of the products of combustion from said fire-box in contact with first the upper and then the lower portions of said retort pipes, said means including a pair of baffle-walls disposed

lengthwise of the kiln between the fire-box 15 and the respective sets of retort pipes and having inner walls inclined upwardly toward each other and forming at their upper ends a reduced outlet for said products of combustion.

Signed at New York in the county of New York and State of New York this 29th day of May, A. D. 1911.
